UNITED STATES PATENT OFFICE.

OSCAR F. ENGEL, OF HARTFORD, CONNECTICUT.

GAME APPARATUS.

Application filed January 17, 1925. Serial No. 3,077.

To all whom it may concern:

Be it known that I, OSCAR F. ENGEL, a citizen of the United States of America, residing at 107 Blue Hills Avenue, Hartford, 5 in the county of Hartford and State of Connecticut, have invented certain new and useful Improvements in Game Apparatus, of which the following is a specification.

This invention relates to a game apparatus 10 for playing a game known as wireless and among the objects of the invention is the provision of a device of this character which is simple in construction and which is effective and quite amusing in action.

15 In the drawing accompanying and forming part of the present specification, I have represented in detail a form of embodiment of the invention which, to enable those skilled in the art to practice the same, will be set forth fully in the following description. I may depart therefrom in a number 20 of respects within the scope of the invention defined by the claims following such description.

25 Referring to said drawing:

Fig. 1 is a plan view of a game apparatus involving the invention.

Fig. 2 is a plan view of a structure comprising part of the appliance.

30 Fig. 3 is a cross section of the structure illustrated in said Fig. 2.

Like characters refer to like parts throughout the several views.

The game apparatus involves in its construction a board or field which may be of any proper material, such as that denoted in a general way by 2 and which is generally made of cardboard and contains on its surface a map of the United States. The map 35 bears on its surface a large number of wireless sending and receiving stations with proper marking, such as WBZ, WTIC, WEAN, WEEZ, etc. In addition to this, the board has upon its corners or other portions station indicators, as 4, which are exactly the same and which have in annular or circular order the stations which appear on the map. Within said stations is a disc 40 5, which is pivoted by an eyelet, as 6, and which has a pointer, as 7, which can be turned to the various stations, as 4. In 45 playing the game, and which usually in-

volves four players, although the number may be either increased or decreased as required, the first player will place his pointer 55 opposite for example the station WLZ. He will then spin the whirligig 8 having a pointer 9 to traverse the stations arranged in circular order. The player then spins the whirligig 8 and when the pointer stops 60 opposite for example the letters KHJ, this will indicate the first move of the first player which means commencing with hole 5 he pegs into hole 10 and then 15 and 20. The game is then continued by a second 65 player and continued in such fashion until the first player runs out one hundred times in which event he wins the game.

When playing the radio game, the player sets the pointer opposite one of the stations 70 on the dial. He then spins the whirligig 8 and scores practically as follows: If the pointer 7 was set at station WEAN and the pointer 9 stops, after being whirled, at WREO the player scores five points by 75 reason of the corresponding letters W. Now, if the pointer had stopped at WEEI the player scores 10 by reason of the first two letters WE corresponding. If the pointer stops at WEAF the player scores 80 15 by reason of the first three letters WEA corresponding. If the pointer stops at WEAN the player scores 20 by virtue of the fact that all four letters correspond. All letters that correspond in the same order 85 obtain five points. The player has one spin and scores whatever comes, then the next player spins and scores, each player spinning in turn and whoever gets 100 first 90 wins the game.

It should be noted that the four dials in Fig. 1 do not spin, whereas the single dial in Figs. 2 and 3 spins quite freely.

What I claim is:

1. A game apparatus comprising a figure 95 representing a map and bearing on it markings denoting wireless stations, a plurality of discs bearing similar marking designations, and a spinning disc having arranged about it similar marking designations, the figure having marks to receive a pointer.
2. A game apparatus comprising a figure 100 representing a map and bearing on it markings denoting wireless stations, a plurality

of discs bearing similarly marked designations and a spinning disc having arranged about it similar marking designations, the figure having holes to receive a peg.

5 3. A game apparatus comprising a figure representing a map of the United States and bearing on it markings denoting wireless

stations, a plurality of discs bearing similarly marked designations, and a spinning disc having arranged about it similar marking designations, the figure having holes to receive a peg.

In testimony whereof I affix my signature.

OSCAR F. ENGEL.
